UNITED STATES PATENT OFFICE

ARMOND STEA, OF BROOKLYN, NEW YORK

DESIGN FOR AN AUTOMOBILE

Application filed December 20, 1930. Serial No. 38,034. Term of patent 7 years.

To all whom it may concern:

Be it known that I, ARMOND STEA, a citizen of the United States, residing at Brooklyn, county of Kings, city of New York, and State of New York, have invented a new, original, and ornamental Design for an Automobile, of which the following is a specification, reference being had to the accompanying drawing, forming part thereof.

I claim:

The ornamental design for an automobile, substantially as shown.

ARMOND STEA.
